UNITED STATES PATENT OFFICE.

HENRY F. LOOMIS, OF READING, PENNSYLVANIA.

FUSE MECHANISM FOR PROJECTILES.

1,198,644.

Specification of Letters Patent. Patented Sept. 19, 1916.

Application filed March 31, 1916. Serial No. 87,884.

To all whom it may concern:

Be it known that I, HENRY F. LOOMIS, a citizen of the United States, residing at Reading, in the county of Berks and State of Pennsylvania, have invented certain new and useful Improvements in Fuse Mechanism for Projectiles, of which the following is a specification.

My invention relates to explosive shells; and it consists in improved means for timing the explosion relative to the moment of discharge from the gun, as fully described in connection with the accompanying drawings and the novel features of which are clearly defined in the claims.

Figure 1 is a longitudinal section of a portion of a projectile embodying my invention in preferred form. Fig. 2 is a front-end view of the same. Fig. 3 is a plan view 20 of the fuse-block; the fuse-intersecting openings in the nose-portion of the shell being indicated by dotted circles. Figs. 4 and 5 are plan views of the separately formed base portion of the fuse-block, and of the securing ring employed. Figs. 6 and 7 are detail views of the fuse-igniter.

The body portion 5 of the shell is formed with a bursting-charge chamber 6 as usual; and the separately formed nose-portion 7 is 30 rigidly screwed into the interiorly screw-threaded circular flange 8 thereof, against a centrally apertured partition wall 9, as indicated. The nose-portion 7 is of ordinary conical form exteriorly, and is hollowed out 35 interiorly to form a fuse-block chamber 10, and provided with a series of fuse-ignition openings 11, 11, 11 into said chamber; these openings being symmetrically grouped around the point of the nose, and extending 40 approximately parallel with the axis of the shell, and each of them being adapted to selectively receive the fuse-ignition device hereafter described.

The fuse-block is adapted to carry a time-45 fuse connection between each of the openings 11 and the bursting-charge chamber 6, and is preferably secured to the nose-portion 7 in two parts 12, 12^a, as shown; the part 12 fitting against the conical inner wall of the 50 chamber 10 and being secured to the nose 7 by a screw-attached ring 13, and the separately removable base part 12^a having a central primer-container 18 arranged in communication with the chamber 6 and forming 55 the terminus of the time-fuse connection to openings 11. The time-fuse connec-

tion indicated consists of a single flexible fuse, 15, which is coiled upon the surface of the fuse-block part 12 in a groove 16 formed therein, so that different portions of its 60 length will be intersected by the respective openings 11, while its lower end is embedded in priming material provided in the primer-chamber 18; the essential effect produced being to provide a different length of fuse 65 between the respective openings 11 and the common primer chamber, whereby the ignition of the fuse through a determined one of said openings will provide a desired time-interval between such ignition and the explosion of the bursting charge.

The fuse-igniter device illustrated in Figs. 6, 7, comprises a tubular casing 20 open at both ends, and formed, as shown, with an interior shoulder 21. Inserted in this casing is a blank-cartridge-explosive 22 seated against said shoulder; a spring 23, bearing upon the cartridge; and a loosely-fitted plunger 24 normally carried by said spring and provided with a pointed lower end or tip 25 80 adapted to explode the cartridge when forcibly moved into contact with the latter. A cross-bar 26 at the top of the casing forms a stop and guard for the spring-pressed plunger. The entire device is adapted to be 85 tightly placed in one or another of the ignition openings 11, as determined by the length of time-fuse to be used; and to operate in exploding the cartridge 22 by the inertia of the plunger 24 at the moment of 90 discharging the projectile from the gun.

The construction specifically shown and described may be readily modified in detail without departing from the invention as defined in the claims.

What I claim is:

1. An explosive shell having a bursting-charge chamber, a nose portion provided with a plurality of fuse-ignition openings, interior time-fuse connection between said 100 chamber and the several openings, and a detonating fuse-igniter selectively placed in one of said openings.

2. An explosive shell having a bursting-charge chamber, a nose portion provided 105 with a plurality of fuse-ignition openings, an interior time fuse having one end arranged in communication with said chamber and different points in its length with a plurality of said openings, and a detonating 110 fuse-igniter selectively placed in one of said openings.

3. An explosive shell having a bursting-charge chamber, a separately formed conically-hollowed nose portion having a plurality of fuse-ignition openings, a fuse-block in said hollowed nose-portion having a flexible fuse arranged with one end in communication with said bursting-charge chamber and different points in its length with said openings, and a detonating fuse-igniter 5 selectively placed in one of said openings.
4. An explosive shell having a bursting-charge chamber, a separately formed con- 10

cally-hollowed nose portion having a plurality of fuse-ignition openings, a fuse-block in said hollowed nose-portion having 15 a primer chamber arranged in communication with said bursting-charge chamber and a flexible fuse communicating at different points in its length with said openings, and a detonating fuse-igniter selectively placed 20 in one of said openings.

In testimony whereof I affix my signature.

HENRY F. LOOMIS.
